MACHINE FOR ORNAMENTING MOULDINGS.

GOTTLIEB F. GOETZE, OF NEW YORK, N. Y.

Letters Patent No. 60,173, dated December 4, 1866.

SPECIFICATION.

TO ALL WHOM IT MAY CONCERN:

Be it known that I, GOTTLIEB F. GOETZE, of the city, county, and State of New York, have invented a new and improved Machine for Ornamenting Mouldings; and I do hereby declare that the following is a full, clear, and exact description thereof, which will enable those skilled in the art to make and use the same, reference being had to the accompanying drawings, forming part of this specification, in which—

Figure 1 represents a longitudinal vertical section of this invention.

Figure 2 is a transverse section of the same.

Figure 3 is a plan of a specimen of the work executed by this machine.

Similar letters of reference indicate like parts.

This invention relates to a machine in which elastic dies are used for the purpose of printing designs on mouldings. These dies are made in the form of rollers, composed of some elastic material, and from their surfaces project the designs to be transferred to the mouldings. The mouldings are carried through under a suitable pattern roller or die, which, being supplied with gum or other sticky material, or ink, produces on the surface of the moulding the required designs, and by applying gold or silver leaf or bronze powder, the effect of these designs can be increased, and ornamented mouldings in great variety can be produced with comparatively little expense.

A represents a bed made of iron, or other suitable material, and supported by legs B. On this bed are secured two strips, C C', of brass or other suitable material, and one or both of these strips are adjustable, so that the distance between their inner edges can be accommodated to mouldings of different size and shape. After said guide strips have been adjusted to correspond to mouldings of a certain size, one moulding after the other is passed through between them by the action of a feed-wheel a, which is mounted on a vertical shaft b. This shaft has its bearings in the bed A, and in a hanger c, secured to the under surface of the bed, and on its lower end is mounted a bevel-wheel d, which gears in a corresponding bevel-wheel e, mounted on the driving shaft, f. To this shaft, motion is imparted by hand or other suitable power. The pattern roller, or die D, is mounted on a shaft g, which has its bearings in two arms h, suspended from a rod i, which is secured in lugs projecting from the outer surface of a plate E; said arms swing freely up and down, and springs j hold the die down upon the surface of the moulding which is to be ornamented. The surface of the die is formed to correspond to the surface of the mouldings, and it is provided with ink or gum by means of an additional roller F, which is hung in swivel arms, k, and depressed on the pattern roller by springs l. The pins which form the bearings for the arms h and k, are removable, so that the rollers can be readily taken out and replaced by others of different shape. The plate E, which supports the rollers D and F, is secured by a screw m, to a carriage G, which moves on a slide H, secured to uprights I, which rise from the bed A. A screw n, serves to adjust the carriage G on the slide, and said slide itself is adjustable up and down on the uprights I, by means of a screw o, which passes down through a cross-bar secured between the upper ends of the standards or uprights I. A screw clamp p, consisting of a cross-bar and thumb-screw, serves to secure the slide H in its position on the uprights I. The roller or die D, is made of a composition of glue and lime, or some other elastic material, so that the same will readily accommodate itself to the surface of the moulding to be ornamented. By the screw o, the pattern roller or die can be depressed on the surface of the moulding, and as said moulding is fed along by the action of the feed-wheel a, the designs which are or may be marked on said roller are transferred to the moulding. If simple gum or other sticking material is used in printing, the marks produced on the surface of the moulding have to be covered with gold leaf, silver leaf, or some other suitable material, but in some cases the designs or ornaments can be transferred to the mouldings in such colors that no further finish is required.

What I claim as new, and desire to secure by Letters Patent, is—

The arrangement of the pattern-wheel D, roller F, springs j and l, adjustable plate E, carriage G, slide H, screws n and o, and clamp p, combined and operating in the manner and for the purpose herein specified.

GOTTLIEB F. GOETZE.
